(57) **CLAIM**

We claim the ornamental design for a panoramic virtual reality camera, as shown and described.

DESCRIPTION

FIG. 1 is an isometric view of a panoramic virtual reality camera.

FIG. 2 is a top view thereof.

FIG. 3 is a bottom view thereof.

FIG. 4 is a first side view thereof; and,

FIG. 5 is a second side view thereof.

The broken lines in the drawings represent unclaimed portions of the panoramic virtual reality camera and form no part of the claimed design.
